STARTING DEVICE FOR ELECTRIC MOTORS

Raymond Knapp, New York, N. Y.

Application October 28, 1936, Serial No. 107,116

7 Claims. (Cl. 172--36)

This invention relates to improvements in a starting device for electric motors and has for an object the provision of a starting device particularly adapted to small motors such as used in 5 motor driven tools wherein the starting mechanism must be small, simple and cheap to manufacture.

Another object of the invention is to provide a 10 device of the character described particularly suited for use in connection with motors used in shaving devices such as that shown and described in the co-pending application, Serial Number 106,527 filed Oct. 20, 1936, entitled Improvements in shaving devices and motors therefor.

A further object is to provide a starting device 15 of the class described constituting an impulse starting mechanism adapted to be mechanically actuated by the insertion of the connection plug into the device.

Other objects and advantages will become apparent during the course of the following specification in connection with the accompanying drawing in which:

25 Figure 1 is a vertical sectional view through the center of the device embodying the invention; Figure 2 is a vertical cross-sectional view of the device shown in Figure 1 on the line 2—2 thereof, the casing on the right, Figure 1, being 30 broken away to show the interior parts;

Figure 3 is a sectional view of the device shown in Figure 2 showing the starting mechanism in two different positions and showing a connecting plug for use with the device; and

35 Figure 4 is a cross-sectional view on the line 4—4, Figure 2.

The numeral 10 denotes a casing forming a handle in which an electric motor of any suitable A. C.-D. C. construction, such as that shown in 40 the aforesaid co-pending application, is mounted and enclosed. This motor has a rotor 11 and a shaft 12 therefor, said shaft being supported in plates 13, 14 so that said rotor may revolve between the poles 15, 16 of a field structure herein 45 after briefly described. A lever 17 is supported on a stud screw 18 mounted in the casing 10; the lower end of this lever being forked and engaging a cam (not shown) on the shaft 12 and the lever is oscillated by the rotation of this cam.

50 The upper end of lever 17 is in operative engagement with the cutter bar 19 so as to oscillate the same below the slotted cutter plate 20 mounted on the head 21 secured to the casing 10. The bar is a tool and the plate is in co- 55 operative working relationship thereto. Hair

entering the slots in the cutter plate will be cut or sheared by the action of the cutter bar in the usual manner.

The field structure has a core portion 22 supporting a winding or windings 23 for energizing the field structure. An interrupter mechanism generally indicated at 24 is provided to cooperate with the field winding to cause the rotor 11 to revolve when current is applied to the device via the circuit terminals 25, 26 which may be in the 10 form of pins, as shown, mounted in a recess or socket 27 within the body of the casing or formed partly in the casing 10 and by the cover or cap thereof 28, and preferably located at the 15 bottom of the casing, as shown.

It will be understood that the construction of the motor and the shaving head per se, the latter being that portion of the device shown above the line A—A, Figure 1, can be varied within wide limits; these may be of the construction 20 shown in the aforesaid co-pending application and the details of construction may be varied within wide limits as these parts and the particular shaving device herein shown and described are merely by way of illustrating the 25 starting device applied to the motor and constituting this invention. However, some of the specific details of the new combination of a shaving device having an automatic starting means for the motor are also claimed herein, the starting device herein described is particularly suited to starting motors in shaving devices but is not limited to use therewith. It may be applied to 30 motors used for any purpose.

This starting device includes a reciprocating 35 arm 29 connected at its lower end to the plunger 30 which is loosely supported to slide in the plate 31 supported in the casing, said plate being preferably of insulating material and supporting the motor terminals 25, 26. The arm 29 is 40 further supported in operative position by a bracket 32 mounted on plate 14 or on any other suitable support. This plate has a slot 33 therein which permits lateral movement of the arm 29 45 therein as presently described.

The hole in the plate 31 through which the plunger projects, is made with rounded edges so that the plunger moves from side to side slightly, as it follows the movement of the arm 29 to which it is attached, or with which it is an integral part. 50 The arm 29 therefore "floats" in its supports 31 and 32 and is free to move laterally as well as reciprocate therein, the lateral movement being very limited at the bottom end.

The arm 29 is connected at any suitable point, 55

such as at 34, with a spring 35 anchored to the field structure of the motor or at any other suitable point and said spring tends to yieldingly hold said arm in the position shown in Figure 2 and 5 Figure 4 and in solid lines in Figure 3, with its plunger end 30 extending freely into the recess 27, the downward movement being stopped by means such as a shoulder 30a on the pin 30 or the turned over edge of 29.

10 The upper end of arm 29 is provided with engaging means such as a claw 36 adapted to engage suitable rotatable means such as a toothed wheel 37 mounted on the motor shaft 12 when the plunger 30 is pressed inwardly.

15 Motors of the type described often require manual starting, some means of mechanically giving the motor armature or rotor an impulse to close a pair of interrupter contacts, and to accomplish this with the mechanism just described, the plunger 30 is pressed inwardly (current being connected to terminals 25, 26). This moves arm 29 upwards from the position shown in Figure 2 and the claw 36 engages the teeth on wheel 37 and rotates the same thereby 20 rotating the shaft 12 and revolving the rotor 11. The claw is held in engagement with wheel 37 by the spring 35, but as the arm and plunger are free to move laterally in slot 33 and plate 31, the claw will ride over the wheel 37 as shown 25 in dot and dash lines, Figure 3, while turning the same and finally the arm and claw will come to rest with the claw above and out of engagement with the wheel 37 as shown in solid lines 30 Figure 3. The plunger 30 should then be held 35 all the way in, in any suitable manner, such as by the connecting plug as presently described.

If the plunger is released, the arm 29 will be retracted by the spring 35 from the position shown in Figure 3 to that shown in Figure 2, the 40 claw riding over the teeth in wheel 37, the arm 29 and plunger 30 being free to move laterally as just described to permit its free return to normal position.

The foregoing starting mechanism forms an 45 impulse starting device for a motor and the preferred method of operating the plunger 30 is shown in Figure 3 wherein a connecting or attachment plug 38 is shown, the insulating body of which is adapted to fit within the recess 27 so that the plug will extend therein as shown in 50 dot and dash lines at 39, Figure 3. This plug has a solid portion 40 adapted to contact with the plunger 30 and force the same inwardly, thereby turning the rotor to close a pair of 55 interrupter contacts, while the plug is being pushed on its way into the recess or socket 27 and after, the live socket contacts 41, 42 have made contact with the motor circuit terminals or contact pins 25, 26. In this way the motor is 60 started.

When plug 38 is withdrawn, the circuit is broken so that there is no current on the motor. The plunger 30 is released when the plug is wholly withdrawn which permits the starting 65 mechanism to return to normal in position for another starting operation.

As the sockets 41, 42 have their outer ends below the outer surface 40 of the body of the plug, short circuits cannot arise by reason of placing the plug with its end 40 against conducting surfaces.

If desired, the terminals 25, 26 may project freely from the casing together with the plunger 30 and the connecting plug may fit over these 70 terminals and be frictionally held in place there-

by, while it operates to press the plunger inward as first described, the socket 27 being omitted.

There is a peculiar cooperative relationship 5 between the starting device, the main subject of this application, and an electrically driven tool, such as the motor driven razor herein described by way of illustration.

This relationship arises mainly from the fact 10 that such electric razors are commonly used in the bathroom where they are subject to an undue amount of moisture.

Heretofore such razors have necessarily had 15 a slot or opening in the casing in which an arm or button was slideable, or some member having a rim corresponding to the wheel 37 shown in this application projecting from the casing in order to be moved by the finger to start the motor.

All such arrangements permit the ingress of 20 hair, soapsuds and the like to the motor parts and the instant invention eliminates possible troubles from these sources.

Such electric razors in the past have commonly had the connecting cord permanently 25 connected to the razor, the free end of the cord being equipped with the usual attachment cord for insertion in the socket. Such arrangements are objectionable because the cord, if of any appreciable length, is much more bulky than the 30 razor itself and is difficult to put away in the small space commonly available in medicine closets and the like where such razors are kept.

In connection with prior art razors having 35 pin terminals thereon so that the cord connects directly thereto, the plug could often be inserted in the razor and the razor would fail to start and if the user forgot to push the starting button but laid the razor down for any reason for a while, the motor would get very hot.

By the improved arrangement herein described, the mere act of inserting the plug in the 40 razor automatically starts the same and the act of disconnecting the plug not only disconnects the razor from the source of current but automatically restores the starting mechanism to a 45 position where it is again ready for operation and it will be readily seen that this invention eliminates the possibility of connecting the razor to a source of current and then forgetting to 50 start the same.

Although the invention has been described 55 in connection with the specific details of preferred embodiments thereof, it must be understood that such details are not intended to be 55 limitative of the invention except insofar as set forth in the accompanying claims.

What is claimed is:

1. In combination, a motor having a winding and a rotor, rotatable means connected to said rotor, an arm adapted to engage said means, a recessed casing enclosing all said parts, means connected to said arm and extending into said recess adapted when pushed inwardly to cause said arm to engage said means to rotate said rotor thereby, and terminals connected to said winding and projecting into said recess adjacent the means connected to the arm for connection to an attachment plug from a source of current for operating said motor, whereby movement of the plug into position on the terminals pushes the arm inwardly and rotates the rotor.
2. In combination, a motor having a winding and a rotor, rotatable means connected to said rotor, an arm adapted to engage said means, a

recessed casing enclosing all said parts, means connected to said arm and extending into said recess adapted when pushed inwardly to cause said arm to engage said means to rotate said 5 rotor thereby, terminals connected to said winding and projecting into said recess for connection to a source of current for operating said motor, and an attachment plug fitting into said recess and having a surface adapted to engage 10 said arm to engage said means to rotate said while said plug is being inserted in said recess, said plug having members adapted to contact with said terminals to supply current thereto when said plug is in said recess.

15 3. In combination, a motor driven device, a casing therefor having a socket therein, terminals for said motor located within said socket, a starting device for said motor, means connected to said starting device and extending within said 20 socket and adapted when pressed inwardly to mechanically start said motor, and means adapted to fit into said socket comprising an attachment plug adapted as it enters said socket to push said means, said plug carrying contacts 25 adapted to connect with said terminals.

4. In combination, an electric motor having circuit terminals, an impulse starting device therefor having a plunger closely adjacent said terminals, and means comprising an attachment 30 plug adapted to actuate said plunger to start said motor and simultaneously connect a supply circuit to said terminals.

5. The combination as claimed in claim 4 where said motor has a casing having a socket therein and said terminals and plunger are located within said socket and said plug is adapted to fit said socket and cooperate with said plunger and terminals for the purposes set forth. 5

6. In combination, a motor having a rotor and shaft, a toothed wheel on said shaft, an arm supported on said motor and having means adapted to engage and turn said wheel when 10 said arm is reciprocated in a plane perpendicular to said shaft, a support for said arm having a slot permitting lateral motion of said arm therein, and means tending to maintain said arm normally out of contact with said wheel. 15

7. An electric tool comprising a casing, a tool supported thereon, a motor enclosed thereby and connected to said tool, a mechanical starting device mounted within said casing, a plunger extending through the bottom of said casing and adapted when manually operated to cause said starting device to start said motor, and motor circuit terminals extending through the bottom of said casing spaced apart and adjacent said plunger, said plunger and motor terminals being mounted on a plate secured to said casing, said plunger and terminals being partly surrounded by said casing whereby contact with the sides of said terminals is prevented. 20 25

RAYMOND KNAPP.

Patent No. 2,077,330.

April 13, 1937.

RAYMOND KNAPP.

It is hereby certified that error appears in the printed specification of the above numbered patent requiring correction as follows: Page 3, first column, line 10, claim 2, for the words "arm to engage said means to rotate said" read second means to push the same inwardly; and that the said Letters Patent should be read with this correction therein that the same may conform to the record of the case in the Patent Office.

Signed and sealed this 1st day of June, A. D. 1937.
